LAMP

Evan D. Williamson, San Francisco, Calif., assignor to E. D. Bullard Company, San Francisco, Calif., a corporation of California

Application December 8, 1934, Serial No. 756,614

3 Claims. (Cl. 240—90)

My invention relates to lamps, and it is among the objects of my invention to improve the visibility of lamps emitting colored light, such as red signal lights, tail lights and the red headlights used on police cars and motorcycles, ambulances, etc.

Another important object of my invention is to provide a lamp construction which will operate to reduce glare in an ordinary headlight.

10 A further object of my invention is to embody the improvements in a lamp construction which is compact and of good mechanical design.

The invention possesses other objects and features of advantage, some of which, with the foregoing, will be set forth in the following description of my invention. It is to be understood that I do not limit myself to this disclosure of species of my invention, as I may adopt variant embodiments thereof within the scope of the claims.

20 Referring to the drawing:

Figure 1 is a side view, partly in section and partly in elevation, showing a preferred embodiment of my invention; and

25 Figure 2 is a similar view showing a modified form of construction.

Figure 3 is a front view of a lamp with its front lens removed, and illustrates another embodiment of my invention.

30 Figure 4 is a side view of a globe carrying a clip, and illustrates another form of my invention.

In terms of broad inclusion, the lamp embodying my invention comprises a source of light, and means sensitive to vibration for disturbing the light beams from the source. When used as a vehicle lamp the light disturbing means is designed to vibrate in response to the vibrations set up in the vehicle.

35 In greater detail, and referring particularly to Figure 1, a preferred form of my invention as embodied in a motorcycle headlight, comprises a housing 2 carried by a support 3 having a suitable clip 4 for mounting the lamp on the motorcycle. The front of the lamp housing is covered by a lens 6 of red glass, held in place by a suitable ring clip 7.

40 Within the rear of the lamp housing a supporting terminal block 8 is provided. This block is preferably fixedly mounted in the housing, such as by the screw 9. A socket 11 is provided on the forward end of the supporting block 8 for receiving the globe 12 which provides the source of light for the lamp. A reflector 13 is also provided in the housing and is arranged about the

5 globe 12 with its mounting on the supporting block 8.

Means, sensitive to the vibration of the motorcycle, are provided for disturbing the light beams from the light source 12 in order to improve the visibility of the lamp. In order to accomplish this result means are preferably provided for mounting the light source 12 and reflector 13 for relative vibration. This is effected by resiliently mounting the reflector on the supporting block 8. 10 As clearly shown in Figure 1, the reflector 13 is supported by arms 14 extending radially and forwardly from the block 8. These arms are of a suitable resilient material, such as spring metal. The rim of the reflector 13 is spaced from the 15 housing 2 and the base of the reflector is provided with an aperture 16 so that the reflector is suspended in free spaced relation relative to the housing 2 and globe 12.

20 By this arrangement the reflector is free to vibrate without striking the adjacent rigid elements of the lamp. Under these conditions the reflector 13 will vibrate rapidly in response to the vibration set up in the frame of the motorcycle. This vibration of the reflector disturbs and 25 breaks up the light beams from the light source 12, with the result that the visibility of the red light emitted by the lamp is materially improved.

Many motorcycle policemen are killed each 30 year because of accidents. A large percentage of these accidents is attributable to the fact that the red headlights employed by traffic patrolmen are not as visible as they should be, with the result that other motorists are not able to give the proper right of way to an oncoming and often 35 fast traveling patrolman. I have found by actual tests that a red headlight embodying the improvements of my invention is clearly and distinctly visible from a much greater distance than the ordinary red headlight.

40 Another important application of my invention is in the red headlights or warning lights of motor cars, such as police cars, ambulances and fire trucks. In the case of automobiles I preferably make the spring arms 14 of a lighter and 45 more resilient material, since the vibration set up in a motor car is less than that existing in the ordinary motorcycle.

Another important application of my invention finds its embodiment in the ordinary tail 50 light of an automobile. It is a well known fact to any motorist that the red tail light of a preceding automobile is not always easy to see. This difficulty is largely corrected by incorporating the improvements of my invention.

40

50

55

The principal idea of my invention is to disturb or break up the light beams emitted by the lamp, so that an ordinary red light is made more distinguishable or visible. The preferred form shown in Figure 1 is one means for accomplishing this result. There are many other means that may be employed for accomplishing the same purpose. Figure 2 shows a construction in which the reflector 17 is fixedly mounted in the housing 18, and the light source or globe 19 is mounted for vibration. In this case the supporting block 21 carrying the globe socket 22 is resiliently mounted on the reflector 17 by suitable spring arms 23. By this arrangement the globe 19 is supported in free spaced relation relative to the housing 18 and reflector 17, so that the light source is free to vibrate.

Another means of disturbing the light beams is shown in Figure 3. In this case both the globe 24 and reflector 25 may be mounted rigidly in the housing 26, in the usual manner. The vibrating member in this construction is an auxiliary lens 27 interposed between the globe 24 and the lens which covers the front of the lamp housing 26. This lens is resiliently suspended by a plurality of springs 28 connected between the periphery of the lens 27 and the rim of the reflector 25. The vibration of this resiliently mounted lens, induced by the vibration of the vehicle, operates to disturb or break up the light beams emitted by the lamp.

Still another form that my invention may take is illustrated in Figure 4, and is adaptable for incorporation in any ordinary lamp. In this case a clip is provided which is mounted on the globe 29 and comprises a vane 31 supported on the clamp portions 32 by thin flexible arms 33. The vane 31 may be of thin sheet metal and is disposed in the path of the light beams emitted by the light source 29. Under conditions of vibration, as in a vehicle, the vane 31 will vibrate across the path of the light beams, and this breaking up of the beams operates to enhance the visibility of the lamp.

Instead of vibrating an element within the lamp, an ordinary lamp may be employed and the lamp as a whole caused to vibrate. This may be effected by providing a suitable mounting for the lamp, such as securing the clamp 45 shown in Figure 1 about a thin rod connected across the handle-bars of a motorcycle. An ordinary lamp mounted on such a thin rod will be caused to vibrate rapidly as a whole. The resulting rapid vibration is such that the light beams are disturbed to a point where the visibility of the light emitted is materially improved.

It is understood of course that any other suitable means could be employed for mounting the lamp to effect its free and rapid vibration. In this connection it is to be understood that the ordinary vibration set up in a lamp by a vehicle is not sufficient to effect the visibility of a lamp. It is only when a mounting means is provided for materially increasing the natural vibration of the lamp that the light beams are disturbed sufficiently to improve the visibility.

The improvements of my invention also find utility in signal lamps, such as found at street intersections. Traffic conditions at street intersections, especially in metropolitan districts, result in considerable vibration in the surrounding structural elements, such as signal lamps. For such installations I preferably employ resilient mounting elements, such as the spring arms 14 and 23 shown in Figures 1 and 2, which are of a very light spring material, so that the suspended element is very sensitive to vibration.

Another very important use of the improvements embodying my invention is in the ordinary headlight for the purpose of reducing glare. A blinding headlight is the source of many accidents. With my improvements, however, the illuminating power is maintained, while at the same time the breaking up of the light beams materially reduces the glare.

I claim:

1. A lamp comprising a light globe, a supporting block, a socket on the block for the globe, a reflector separate from and spaced freely from the globe, and a plurality of substantially flat spring arms each connected at one end to the block and at the other end to the periphery of the reflector, said arms extending radially outwardly from said block and curving forwardly toward the reflector.

2. A lamp comprising a light globe, a fixed supporting block, a socket on the block for the light globe, a vibratile reflector, and a plurality of substantially flat spring arms each connected at one end to the block and at the other end to the periphery of the reflector, said arms extending radially outwardly from said block and curving forwardly toward the reflector.

3. A lamp comprising a light globe, a fixed reflector, a vibratile supporting block, a socket on the block for the light globe, and a plurality of substantially flat spring arms each connected at one end to the block and at the other end to the periphery of the reflector, said arms extending radially outwardly from said block and curving forwardly toward the reflector.

EVAN D. WILLIAMSON.
